UNITED STATES PATENT OFFICE.

WELLES M. POST, OF WILKINSBURG, PENNSYLVANIA.

BOND-WIRE HOLDER AND PROTECTOR.

Application filed March 26, 1923. Serial No. 627,930.

My invention relates to bond-wire holders for holding in place the bond-wires between railroad rails.

The purpose of my invention is to provide 5 a bond-wire holder which is inexpensive to manufacture and easy to place upon the wire and which supports the wire from displacement laterally in any direction.

Further purposes will appear in the specification and in the claims.

I have preferred to illustrate my invention by but two forms, selecting forms that well illustrate the principles involved and which moreover have been found well 15 adapted to the needs of service.

Figures 1 and 2 are respectively a broken plan and an elevation of two bonded rails supplied with my holders for maintaining the bond-wire in place.

20 Figure 3 is a section through the line 3—3 of Figure 2.

Figure 4 is a perspective view of the holder used in Figures 1 to 3.

25 Figure 5 is a section view similar to that of Figure 3 but with the holder modified to accommodate a different relation with the fish-plate.

Figure 6 is a perspective view of the modified form of Figure 5.

30 Figure 7 is a broken section to illustrate one way of connecting my holder to the fish-plate.

Describing in illustration and not in limitation and referring to the drawings:—

35 Prior to my present invention bond-wire holders have not themselves laterally supported bond-wires in all directions, but have depended upon one side for engagement with a co-operating fish-plate to prevent 40 lateral displacement in that direction. This dependence for the co-operation of the fish-plate has not been wholly satisfactory in that accidental distortion of the holder, as by a blow from a pick of a careless work- 45 man, has in many instances either left the hold insecure or actually torn it loose. It is to overcome this fault that I have devised my present invention whereby any ordinary accidental distortion of the holder will still 50 leave the bond-wires securely locked to the holder laterally in all directions.

In the drawings the rails 10 and 11 united by fish-plates 12 and 13 and track bolts 14 are bonded electrically by bond-wires 15 55 having their ends respectively penetrating and plugged to the rails at 16.

In their passage from rail to rail the bond-wires are led along the top of the fish-plate to be well out of the way of the picks of workmen and held there by my 60 holder 17 with lateral support from the holder itself in every direction. The holder which is made of sheet metal is held in place by the head 18 of the track bolt 14.

The holder is provided with prongs 19 65 and 20 relatively spaced at 21 to pass the wires when held temporarily transverse thereto (i. e., when canted laterally) and these prongs pass in reverse directions about the wires so as together to include the wires 70 when in holding position, thereby affording lateral support to the wires in all directions, irrespective of the proximity of the fish-plate, and of accidental distortion.

The body of the holder and the inner of 75 prongs (the one toward the fish-plate) are bent into accommodation with the fish-plate; thus in Figures 1 to 3 where the wires are led along the top of the fish-plate these 80 accommodating bends take the form shown in Figure 4 at 22, 22', while in Figure 5 where the wires are led along the top of the bottom flange the accommodating bends are as shown at 23, 23' in Figures 5 and 6.

A perforation 24 for use in securing the 85 holder to the fish-plate is likewise accommodated to existing need. Usually it is an oval adapted to fit the oval shank of the track bolt, and this oval is either open as in Figure 4, for sliding on or off without taking out the track bolt or closed as at 24' in Figure 6. Sometimes the track bolt is not used to secure the holder which is then held in place by a plug 25 as shown in Figure 7 and in this event the hole 24 is adapted 90 to fit the plug. Evidently these minor modifications are all such as do not affect the broad invention.

In view of my invention and disclosure 100 modifications and variations to meet individual whim or particular need will doubtless become evident to others skilled in the art and I claim all such modifications and variations in so far as they fall within the reasonable spirit and scope of my invention.

Having thus described my invention, what I claim as new and desire to secure by Letters Patent is:—

1. In a device for use with electrically 110 bonded rails, a bond wire and a sheet metal holder for the bond wire having one end bifurcated, the metal at the bifurcation be-

ing spaced longitudinally of the rail and in planes perpendicularly thereto to provide for insertion of the bond wire through the bifurcation and its retention against movement in opposite directions by the ends adjacent the bifurcation.

2. In a device for use with electrically bonded rails, a bond-wire, and an integral bond-wire holder intermediate of the bond connections insertible about and removable from the wire having oppositely facing, longitudinally spaced prongs having spaces between them for diagonal insertion and removal of the bond wire, and laterally supporting the wire from displacement in every direction.

3. In a device for use with electrically bonded rails, a bond-wire, and an integral sheet metal bond-wire holder intermediate of the bond connections having prongs at the same end of the sheet, each engaging the wire in two directions and together forming a single opening and laterally supporting the wire from displacement in every direction.

4. In a device for use with electrically bonded rails, a bond-wire, a holder therefor and two prongs on the holder relatively spaced longitudinally of the wire, laterally open to pass the wire in transverse position and passing in reverse directions partially

about the wire to together include the wire.

5. In a device for use with electrically bonded rails, a bond-wire, a fish-plate, bolts therefor holding it to both rails, a holder for the wire accommodated to the fish-plate and held thereto by one of the bolts and having two oppositely facing prongs extending from one end of the holder relatively spaced longitudinally of the wire to pass the wire in transverse position and passing in reverse directions partially about the wire to together include the wire.

6. A bond wire, in combination with a support for the wire adapted to hold it along a rail, comprising a plate having the ends slitted and bent in planes perpendicularly of the plate so as to face oppositely to permit the bond wire to pass between the ends in one position of the plate and in the normal position of the plate to be retained in opposite directions of movement by different ends.

7. In longitudinally bonded rails, a bond-wire and a single piece bond-wire holder located intermediate of the bond-wire connections and having oppositely facing longitudinally spaced prongs bearing on opposite sides of the bond-wire whereby the wire may be removed by canting of the holder.

WELLES M. POST.
